Term of patent 14 years

(Cl. D86—10)

FIG. 1.

FIG. 2.

The essential features of my design reside in the portions shown in full lines.

I claim:

The ornamental design for a pin curl clip, as shown and described.
